BOILER CONSTRUCTION

Frank L. Cormier, East Braintree, Mass., assignor to Massachusetts Engineering Co., Inc., North Quincy, Mass., a corporation of Massachusetts

Application March 10, 1938, Serial No. 195,115

8 Claims. (Cl. 29—157.4)

This invention relates to boiler construction and more particularly to low pressure horizontal fire-box boilers for heating purposes. These boilers ordinarily comprise a cylindrical water chamber portion and a rectangular fire-box at one end of such portion and beneath an extended part of the water chamber. The primary object of my invention resides in an improved boiler construction of this nature and in the novel method of producing the same.

In accordance with one aspect of my invention I form the outer shell of the boiler, including both the cylinder and fire-box portions, from a single sheet metal blank. The blank is first sheared inwardly from two opposite edges. The unsheared portion is then curved to arcuate configuration after which two wings of one sheared portion are curved to form a cylinder together with the curved unsheared portion, and the other two wings of the sheared portion are brought into parallelism to form the side walls of the fire-box. This novel boiler shell and the method of producing the same comprises one of the objects of my invention.

A further object of the invention resides in the production of a novel U-shaped member also constructed from a single sheet metal blank and adapted to cooperate with the above mentioned shell to form an outer wall of the boiler and a flue sheet for the fire-box. This U-shaped member is adapted to be joined to the shell and other preshaped and cooperating pieces are likewise adapted to be joined thereto in a convenient and relatively simple manner to form the fire-box and provide a water jacket for the walls thereof in communication with the water chamber.

With the above and other objects in view as will hereinafter appear my invention consists in the features of construction herein described and one form of which is illustrated in the accompanying drawing wherein:

Fig. 1 is a side elevation of a boiler embodying my invention.

Fig. 2 is a rear end elevation thereof.

Fig. 3 is a cross sectional view taken on line 3—3 of Fig. 1.

Fig. 4 is a longitudinal sectional view taken on line 4—4 of Fig. 2.

Fig. 5 is a plan sectional view taken on line 5—5 of Fig. 1.

Fig. 6 is a plan view of a flat steel sheet used to form the outer shell of the boiler.

Fig. 7 is a perspective view of the boiler shell formed from this sheet.

Fig. 8 is a plan view of a flat sheet used to form

a U-shaped member to provide an outer wall for the boiler and a flue sheet for the fire-box.

Fig. 9 is a perspective view of the U-shaped member thus formed.

Figs. 10—13 are perspective views of filler pieces 5 used to complete the fire-box.

Referring first to the construction of the outer shell of the boiler, 10 indicates a flat sheet metal blank of rectangular shape. I shear this blank inwardly along a common axis at 12 from opposite edges of the blank, leaving an unsheared intermediate portion, this intermediate portion is then curved to arcuate shape, as shown in Fig. 7, and such curvature is continued throughout the two wings 14 of the blank to form a cylinder 16. 15 The other two wings 18 are brought into parallelism to form the side walls of the fire-box portion of the shell, this portion being that part of the boiler rearwardly of the cylindrical portion and containing the fire box chamber. The two 20 leading edges of the wings 14 are joined together in any suitable manner.

In Fig. 8 is illustrated a second flat sheet metal blank 20 having a wider end portion 22 arcuately recessed at 24 to a curvature corresponding to the curvature of the shell cylinder 16. The other end portion 26 of this blank is relatively narrower and is apertured at 28 to receive the boiler tubes, this portion having its end edge convexly curved as indicated at 30. After being formed to the condition shown in Fig. 8, this blank is bent to the U-shape shown in Fig. 9 wherein the blank embodies two parallel end portions 22 and 26 and an intermediate connecting portion 32, the blank being bent along the broken lines shown in Fig. 8.

The U-shaped blank is so assembled to the outer boiler shell that the end portion 22 and intermediate portion 32 respectively provide front and bottom walls of the water chamber, and the 40 end portion 26 provides a flue sheet in the fire-box. In its assembled relation, the arcuate edge 24 is joined to the front end of the cylinder at 34 and the side edges 36 are joined to the edges of the wings 18 at 38, as by welding. The fire-box is then completed by joining side pieces 40 to the flue sheet 26 and to the wings 18, the edges 42 of the pieces 40 being joined to the edges 44 of the flue sheet and the flanged edges 46 being joined to the bottom and front edges 48 of the wings 18. A curved top plate 50 is joined to the curved edge 30 of the flue sheet and along its end edges 52 to the top edges 54 of the pieces 40. Thus the fire-box is completed and a 50 water jacket open to the main water chamber 55

of the boiler is formed forwardly of the flue sheet at 56 and along both sides of the fire-box at 58, a tube 68 providing for circulation of water between the side walls 58 of the jacket.

5 The front end of the cylindrical chamber is closed by a flue sheet 60 provided with tube apertures 62. The tubes 64 are mounted in the flue sheets 26 and 60 in the usual manner and the rear end of the water chamber is closed by 10 a plate 66.

It will now be apparent that I have produced a superior boiler of the nature herein disclosed by a novel and ingenious method which results not only in a great saving in time, labor and 15 material but which also produces a superior product.

Having thus described my invention, what I claim as new and desire to secure by Letters Patent is:

- 20 1. The method of forming the outer shell of a boiler having a cylindrical portion and an adjacent fire-box portion, which comprises shearing a suitable sheet-metal blank inwardly from two opposite edges to form two wings at each 25 of said edges, bending one portion of the blank together with the attached two wings to form a cylinder, and utilizing the other portion of the blank together with the attached two wings to form the fire-box portion of the shell.
- 30 2. The method of forming the outer shell of a boiler having a cylindrical portion and an adjacent fire-box portion, which comprises shearing a suitable sheet metal blank inwardly along a common axis from two opposite edges to form two wings at each of said edges, bending one portion of the blank together with the attached two wings to form a cylinder, and placing the other two wings in parallelism to form the side walls of the fire-box portion of the shell.
- 35 40 3. The method of forming the outer shell of a boiler having a cylindrical portion and an adjacent fire-box portion, which comprises shearing a suitable sheet metal blank inwardly along a common axis from two opposite edges to form two wings at each of said edges, bending the unsheared intermediate portion of the blank to arcuate configuration, bending two oppositely disposed wings to conform to said configuration and form a cylinder with the intermediate portion 45 of the blank, and continuing the other two wings into parallelism beyond and tangentially of said arc.
- 50 4. The method of constructing a boiler, which comprises forming from a single piece of sheet metal an outer shell having a cylindrical portion and an adjacent fire-box portion with parallel side walls, providing a sheet metal blank with one end arcuately recessed to correspond to the curvature of said cylindrical portion of the 55 shell and the other end portion apertured to receive and support one end of the boiler tubes, bending the blank to U-shape with the two end portions in spaced and parallel relation, and assembling the blank and shell by joining said recessed portion of the blank to the cylindrical portion and side walls of the shell in position wherein the apertured end portion of the blank forms the flue sheet of the fire-box.

5. The method of constructing a boiler, which comprises forming an outer shell having a cylindrical portion and an adjacent fire-box portion with parallel side walls, arcuately recessing one end of a sheet metal blank to a curvature corresponding to said cylindrical portion of the shell and aperturing the other end portion of the blank to receive and support one end of the boiler tubes, bending the blank to U-shape with the two end portions in spaced and parallel relation, assembling the blank and shell by joining said recessed portion of the blank to the cylindrical portion and side walls of the shell in position wherein the apertured end portion of the blank forms the flue sheet of the fire-box, and 15 providing inner sheet metal fire-box walls joined to the shell and to the edges of the flue sheet.

6. A boiler comprising an outer shell having a cylindrical section and a fire-box section formed from a single sheet metal blank having its intermediate portion curved to form the top portion of the boiler and having the ends of one portion of the sheet joined to complete the cylindrical section, the fire-box section having its top portion integrally attached to and in the same 20 curved plane as the top arcuate portion of the cylindrical section and having spaced and parallel side walls integral therewith, a combined flue sheet and outer wall forming sheet formed from a single sheet metal blank having its intermediate 25 portion bent to U-shape and providing spaced and parallel end portions, one of said portions having its free end arcuately recessed and joined therewith to one end of the cylindrical shell and the other portion being apertured to receive 30 the ends of boiler tubes and forming the flue sheet of the fire-box, and means cooperating with and joined to the edges of said flue sheet for providing water jacketing top and side walls for the fire-box.

7. A boiler comprising an outer shell having a cylindrical section and a fire box section formed from a single sheet metal blank having its intermediate portion curved to form the top portion of the boiler and having the ends of one portion of the sheet joined to complete the cylindrical section, the fire box section having its top portion curved to correspond to the cylindrical section and having spaced and parallel side walls integral therewith, a combined flue sheet and outer wall forming sheet formed from a single sheet metal blank having its intermediate portion bent to U-shape and providing spaced and parallel end portions, one of said end portions having its free end arcuately recessed and joined therewith to one end of the cylindrical shell and the other portion being apertured to receive the ends of boiler tubes and forming a flue sheet of the fire box.

8. The boiler defined in claim 7 wherein the intermediate and recessed end portions of said U-shaped blank are wider than the other end portion thereof and are joined along their edges to the shell, and means cooperating with and joined to the edges of said flue sheet for providing water jacketing top and side walls for the fire box.

FRANK L. CORMIER.
